SITTING KITTY DOLL

Nancy J. Ott, 33879 Nebraska Lane,
Yucaipa, Calif. 92399

Filed Feb. 9, 1970, Ser. No. 21,360

Term of patent 14 years

Int. Cl. D21—02

U.S. Cl. D34—2

FIG. 1.

FIG. 2.

FIG. 4.

FIG. 3.

FIG. 1 is a side elevational view of a sitting kitty doll showing my new design.

FIG. 2 is a front elevational view of FIG. 1.

FIG. 3 is a plan view of FIG. 1.

FIG. 4 is a longitudinal vertical cross-sectional view of the invention to a slightly reduced scale.

I claim:

The ornamental design for a sitting kitty doll, as shown.
